UNITED STATES PATENT OFFICE

HERBERT G. IRWIN, OF AMARILLO, TEXAS

FEED VALVE FOR ACETYLENE GENERATORS

Application filed August 25, 1927. Serial No. 215,282.

This invention relates to improvements in carbide feed valves for automatic acetylene generators of the diaphragm controlled valve feed type.

5 The object of my invention is to provide new and useful improvements in a carbide feed valve for an automatic acetylene generator.

A further object of my invention is to provide an underneath opening feed valve that 10 will permit removal of a separable hopper bottom without removing the feed valve which, is connected with a control mechanism above the carbide outlet and hopper bottom 15 through the medium of a stem.

A further object of my invention is to provide convenience in taking down for cleaning or otherwise and assembling a generator having a separable carbide hopper with an 20 interposed separable bottom and a carbide feed valve adapted to open below a carbide outlet in the hopper bottom and actuated by an automatic control directly above the carbide outlet.

25 A further object of the invention is to provide convenience in removing a feed valve that opens below a carbide outlet in an interposed separable hopper bottom and actuated by an automatic control mounted above said outlet 30 without removing the hopper bottom.

With these and other objects in view, my 35 invention consists in the arrangement, combination and construction of the various parts of my improved valve, as described in the specifications, claimed in the claim, and shown in the accompanying drawings, in which:

Figure 1 is a view of the upper portion of 40 an acetylene generator with walls cut away showing my improved feed valve connected with an automatic control, the valve being in closed position.

Figure 2 is an enlarged sectional view 45 through a feed valve constructed in accordance with my invention.

Figure 3 is a view of the under side of the 50 valve shown in Fig. 2.

Figure 4 is a sectional view through an alternate form in which my invention may be 55 accomplished.

Referring to the accompanying drawing, the upper portion of the water chamber of an acetylene generator is indicated by numeral 1, the removable carbide hopper 2, an interposed separable hopper bottom 3, and for an 55 instance, one type of automatic feed control 4, mounted in the carbide hopper.

The carbide feed valve 5, is an inverted cone and as for an instance in Fig. 1, is suspended from the under side of the control diaphragm 4A, by a stem 6. The sides of the valve taper from a cylindrical base 5B, which fits with slight lateral play in the carbide outlet opening 7, in the small end of the conical hopper bottom. The opening 7 is 60 closed against the passage of carbide when the valve is drawn into it as shown. A downward movement of the control diaphragm lowers the valve out of the outlet in feeding carbide automatically. In other words, this 65 feed valve is merely drawn into the carbide outlet to close the latter instead of its tapering sides seating against the lower edge of the carbide outlet as is common with feed valves adapted to open downward from the 70 outlet to feed carbide. The valve may be moved up and down on the stem by means of screwthreads 5C and 6C, to bring the cylindrical base 5B in proper adjustment 75 with the outlet 7 in setting the valve in closed 80 position. The valve may be locked on the stem by means of a cotter 6D, as shown in Fig. 2, or solder may be fused in the screwthreads of both valve and stem and adjustment made while hot. It is preferred to make 85 the valve hollow on the under side to reduce material and weight. When this valve is used with a control diaphragm without a stop or definite normal position which will limit upward movement of the feed valve with the base 5B in the outlet, a stop (not shown) to limit upward movement of the valve may be 90 provided in the form of a lug formed on the valve stem some distance above the valve that will abut the under side of a shoulder formed 95 in the valve stem guide, when the base 5B slides into the outlet.

It will be seen that such a feed valve, while suspended by a stem from above the carbide outlet and adapted to open below the outlet, 100

will permit the removal of the carbide hopper or control mechanism with the valve without removing the valve from the stem, or removing the hopper bottom from the water chamber with the hopper, by reason of the valve 5 sliding upward through the carbide outlet with the control when the hopper head 8, or the hopper is removed. In a portable generator having an interposed separable hopper bottom and a removable hopper with a control carried thereby, or without a separable hopper bottom but with removable hopper head carrying the feed control, and the hopper bottom carrying a splash shield on its 10 under side connected with shield opening and closing means below the bottom, such a valve adds to convenience in assembling the generator at the factory and also adds to convenience in taking the generator down in the field for cleaning or repair. The valve may 15 be used on both stationary and portable generators, when it is desired to mount the feed control above the carbide outlet and use a feed valve that opens below the carbide outlet.

20 While I have shown and described a carbide feed valve constructed in accordance with my invention, it will be manifest to persons skilled in the art that changes may be made in minor details of structure in adapting the device to use in various generators, and slight changes in the mode of operation of same within the scope of the appended claim, without departing from the spirit of the invention; it is, therefore, to be understood 25 that this invention is not to be limited to the details described and shown.

What I claim is:—

30 A suspended carbide feed valve comprising a cylindrical base with an upper conical pilot 35 having internal screw-threads that engage external screw-threads on the lower end portion of a depending stem whereby the valve may be moved up or down on the stem to facilitate adjustment of the valve for closed 40 position and means for locking the valve on the stem.

HERBERT G. IRWIN.
